INSOLE AND METHOD OF AND MATERIAL
FOR MAKING THE SAME

Arthur C. Sewall, Auburn, Maine

Application October 8, 1935, Serial No. 44,022

9 Claims. (Cl. 12—146)

My invention, which relates to insoles and to methods of and material for making the same, will be best understood from the following description when read in the light of the accompanying drawing, the scope of the invention being more particularly pointed out in the appended claims.

In the drawing:—

Fig. 1 is a plan of an insole constructed according to the invention;

Fig. 2 is a section on the line 2—2 of Fig. 1;

Fig. 3 is a plan of a modified form of insole;

Fig. 4 is an enlarged fragmentary section of the ball portion of the insole according to Figs. 1 and 2; and

Fig. 5 is a fragment of a strip from which the insole may be formed.

Referring to the drawing, the insole illustrated by Figs. 1 and 2 comprises the ball portion 1 and shank portion 3 formed of relatively flexible material such as rubber impregnated bibulous paper or flannel, or other impregnated fibrous material, the opposite end edges of which are skived, as indicated at 5, and are cemented to the corresponding skived end edges of the toe portion 7 and heel portion 9, respectively.

The toe and heel portions preferably are made of relatively stiff tough material, such as fiberboard or the like, so as, among other things, to prevent buckling thereof during the lasting operation and pulling through of the lasting and heel attaching nails.

To insure increased flexibility of the ball and shank portions the same are transversely slashed, preferably along closely adjacent parallel lines 11. This slashing may be done by passing the insole between a set of parallel scoring knives and a cooperating roll, the distance between the edges of the knives and the roll being adjusted to slash the insole to a depth preferably corresponding to from one-quarter to one-half its thickness. Due to the nature of the material, which is preferably rubber impregnated bibulous paper formed of long alpha cellulose wood fibers, or rubber impregnated flannel, the insole is scored in the form of grooves with the surface of the insole between the grooves rounded, as best shown in Fig. 4, so as to present what in effect amounts to rounded groove edges 13, as indicated in Fig. 4, the slashing being more in the nature of pressed-in indentations than cuts. This construction avoids the presence of rough edges along the slashed lines of the insole and increases the facility with which the ball portion of the insole may be bent to concave its upper side when the shoe is worn.

the slashing preferably, but not necessarily, being at the upper surface of the insole.

If desired, only the ball portion of the insole may be slashed in the form of the invention shown by Figs. 1 and 2. If a stiff shank is desired the heel and shank portions may be formed of an integral piece 15 of relatively stiff tough material, such as fiberboard and the like, as shown in Fig. 3, in which case only the ball portion of the shoe will be formed of impregnated bibulous paper, flannel, or the like.

Although the insoles may be slashed individually, preferably, properly to position and form the slashing, and to secure a plurality of insoles each of the same character and flexibility, they are cut from a sheet of strip material which is slashed, using the edges of the sheet as a guide, prior to cutting the insoles therefrom. Such a sheet, as indicated in Fig. 5, may comprise a central portion or band 17 of material of which the shank and ball portions, or the ball portion alone, is formed, depending upon whether the insole illustrated by Fig. 1 or Fig. 3 is desired. The opposite skived edges of this band 17 are cemented to skived edges of bands 19 and 21 respectively of material of which the toe portion and heel portion, or one-piece heel and shank portion, is formed. From this sheet a plurality of insoles may be cut, say by a stamping operation, as indicated by dotted lines 23 in Fig. 5.

Besides assuring uniformity and the same flexibility in each of a plurality of insoles, when cut from the above described sheet or strip, the shoe manufacturer by use of the same is enabled readily to have the slashing at right angles or other desired angle to the longitudinal axis of the insole, and along straight lines, because the edge of the sheet not only serves as a guide when operating upon it to slash it but as a guide when the sheet is presented to the stamping machine. Further, it has been found that when the insoles are slashed separately the edges of the slashed portion tend to roughen due to the action of the slashing knives which at those edges tend to cause projections in the slashed material at the end of each slash line. By stamping or otherwise cutting the insoles from a preslashed sheet this is avoided. It has further been found that it is difficult, when slashing the insoles separately, not only to control the position of the slashing and secure straight slash lines, but to control the depth of the slashing and secure slash lines of a uniform depth. These difficulties are avoided by slashing the long sheets and cutting or stamping the insoles from them.

It will be understood that wide deviations may be made from the forms of the invention described without departing from the spirit thereof.

I claim:

5. 1. The method of forming a plurality of insoles which are uniform in respect to flexibility, having transversely slashed ball portions of material of different flexibility from that of the toe and heel portions, which comprises forming a band of the 10 material of the ball portion of width not less than the length of that portion and of length greater than the combined widths of the plurality of insoles, cementing to one edge of said band the edge of a band of material of the toe portion of width not less than the length of that portion, cementing to the opposite edge of the first mentioned band the edge of a band of material of the heel portion of width at least the length of that portion, operating upon the sheet thus formed to 15 slash the first mentioned band longitudinally thereof, and cutting the insoles from the slashed sheet transversely thereof.
2. The method of forming a plurality of insoles which are uniform in respect to flexibility, having transversely slashed ball portions of material of different flexibility from that of the toe and heel portions, which comprises forming a band of the material of the ball portion of width equal to approximately the length of that portion 20 and of length greater than the combined widths of the plurality of insoles, cementing to one edge of said band the edge of a band of material of the toe portion of width not less than the length of that portion, cementing to the opposite edge of the first mentioned band the edge of a band of material of the heel portion of width at least the combined lengths of the heel and shank portions, operating upon the sheet thus formed to slash the first mentioned band longitudinally thereof, and 25 cutting the insoles from the slashed sheet transversely thereof.
3. Blanks for forming a plurality of insoles consisting of sheet material comprising a band of flexible material having longitudinally extending slashes, the surface portions between the slashes having rounded edges at the slash lines, and, at opposite edges of said band, bands of stiff tough material secured thereto by skived cemented seams.
4. Blanks for forming a plurality of insoles consisting of sheet material comprising a band of flexible impregnated fibrous material having longitudinally extending slashes, the surface portions between the slashes having rounded edges at the slash lines, and, at opposite edges of said band, bands of stiff tough fiberboard or the like secured thereto by skived cemented seams.
5. Blanks for forming a plurality of insoles consisting of sheet material comprising a band of flexible rubber impregnated bibulous paper material having longitudinally extending slashes, the surface portions between the slashes having rounded edges at the slash lines, and, at opposite edges of said band, bands of stiff tough fiberboard or the like secured thereto by skived cemented seams.
6. Blanks for forming a plurality of insoles
- consisting of an elongated sheet of width at least the length of the insole having a longitudinally extending intermediate zone slashed along longitudinally extending closely adjacent lines for increasing the flexibility of said zone transversely thereof, the surface portions between the slashes having rounded edges at the slash lines, said zone being of width not less than approximately the length of the ball portion of the insole, and, at opposite sides of said zone and contiguous therewith, zones of less flexibility of width at least that of the toe and heel portions of the insole respectively.
7. Blanks for forming a plurality of insoles consisting of an elongated sheet of width at least the length of the insole having a longitudinally extending intermediate zone slashed along longitudinally extending closely adjacent lines for increasing the flexibility of said zone transversely thereof, the surface portions between the slashes having rounded edges at the slash lines, said zone being of width approximately the length of the ball portion of the insole, and, at opposite sides of said zone and contiguous therewith, zones of less flexibility one of which is of width not less than the approximate length of the toe portion of the insole and the other of width at least the approximate combined lengths of the shank and heel portions of the insole.
8. The method of forming a plurality of insoles which are uniform in respect to flexibility, having transversely slashed ball portions of material of different flexibility from that of the toe and heel portions, which comprises forming a sheet, 30 of width at least the length of the insole and of length greater than the combined widths of the plurality of insoles, having an intermediate band of material of the ball portion of width not less than the length of that portion and having, at opposite edges of said band and contiguous therewith, bands of material of the toe and heel portions respectively, of widths not less than the lengths of those portions, respectively, operating upon the material of said intermediate band to slash it longitudinally thereof, and cutting the insoles from said sheet transversely thereof.
9. The method of forming a plurality of insoles which are uniform in respect to flexibility, having transversely slashed ball portions of material of different flexibility from that of the toe and heel portions, which comprises forming a sheet, 35 of width at least the length of the insole and of length greater than the combined widths of the plurality of insoles, having an intermediate band of material of the ball portion of width equal to approximately the length of that portion and having, at opposite edges of said band and contiguous therewith, bands of material of the toe and heel portions respectively, one of width not less than the length of the toe portion and the other of width not less than the combined lengths of the heel and shank portions, operating upon the material of said intermediate band to slash it longitudinally thereof, and cutting the insoles 40 from said sheet transversely thereof.

ARTHUR C. SEWALL.
